C. W. Shiffman
ATTORNEY

UNITED STATES PATENT OFFICE.

HENRY MANNING COGAN, OF BROOKLYN, NEW YORK.

FUSE.

1,278,110.

Specification of Letters Patent. Patented Sept. 10, 1918.

Application filed April 13, 1917. Serial No. 161,885.

To all whom it may concern:

Be it known that I, HENRY MANNING COGAN, a citizen of the United States, and resident of the borough of Brooklyn, county 5 of Kings, city and State of New York, have invented certain new and useful Improvements in Fuses, of which the following is a specification.

The device, the subject of this invention 10 may be more definitely termed a refillable fuse for electric circuits of comparatively small current.

This fuse is of the so called cartridge type wherein a cylinder of non-conductive material is closed by caps of metal and between these metallic caps and interior of the non-conducting cylinder a fuse link is arranged.

The principal object of my invention is to 20 so construct the cartridge that the link or fuse proper may be changed or a new link inserted when an increase of current has burned out or disrupted the link contained in the fuse.

The means for accomplishing the desired 25 results and the construction of the device will be fully set forth as the specification progresses.

The following is what I consider a good 30 means of carrying out this invention and, the accompanying drawings should be referred to for a complete understanding of the specification which follows:—

In the drawing.

Figure 1 shows a side elevation of a complete device.

Fig. 2, a central longitudinal section thereof.

Fig. 3, an end elevation.

Fig. 4, an end elevation partly in section.

Fig. 5 shows a side elevation with one cap removed.

Similar reference numerals indicate like parts in all the figures where they appear.

My fuse is constructed in a manner very 45 similar to the ordinary cartridge fuse and is therefore provided with a cylinder 1, of non-conducting material of any desired nature. Arranged one at each end of the cylinder 1, are cupped shaped members 2 and 3 formed of metal and these cupped shaped members project over the cylinder 1, to a considerable extent.

Contact with this cartridge fuse is made by means of clips not shown which engage 55 around the members 2 and 3.

Each of the members 2 and 3 are perfor-

rated and in the perforations I introduce screws as shown at 4 and 5.

In the tubular member 1, I arrange metallic blocks 6 and 7 each having a tongue 60 as shown at 8 and 9 which enters suitable perforations in the side of the member 1, and these blocks 6 and 7 are provided with screw threaded perforations into which the screws 4 and 5 are introduced.

Each of the blocks are also provided with projections or trunnions 10 and 11, which are received in slots or recesses which enter from each end of the tubular member 1.

The fuse or link shown at 12 has each of 70 its ends inturned at 13 and 14 and these in-turned ends are perforated and rest upon the outer faces of the blocks 6 and 7. It is obvious that the link 12 is placed in position before the screws 4 and 5 are introduced and 75 that when the screws are entered through the perforations in the caps 2 and 3 through the ends 13 and 14 of the fuse link 12 and into the screw threaded perforations of the blocks 6 and 7 and are tightened into the 80 blocks, the blocks will be drawn outward and the ends of the fuse link will be clamped securely between the blocks 6 and 7 and their adjacent caps 2 and 3 making a satisfactory electrical contact between the fuse link and 85 the caps 2 and 3.

The blocks 6 and 7 are supported in position to be engaged by the screws 4 and 5 by means of the trunnions 10 and 11 and the projections 8 and 9, and the projections 8 and 90 9 also serve to prevent the caps 2 and 3 being blown off or displaced, when the fuse link 12 is disrupted or broken.

I may weaken the fuse link to provide a blow point and I may change or increase 95 or diminish the size of any of the parts and other modifications may be made within the scope of the appended claims.

Having carefully and fully described my invention what I claim and desire to secure 100 by Letters Patent is:—

1. A cartridge fuse having a cylinder, a cupped shaped member at each end thereof, blocks wholly within said cylinder and movably secured therein and a fuse link adapted 105 to be engaged between said blocks and their adjacent cupped shaped members.

2. A cartridge fuse having an insulating casing provided with slots and a perforation at each end thereof, contact members 110 one at each end of said casing, blocks supported within said casing and interior of

- the ends thereof, said blocks having projections adapted to enter said slots to move therein, a screw passing through each of said contact members and into a block, a fuse link each end of which is engaged by the movement of one of said blocks and projections from said blocks and engaged in the wall of said casing to limit the movement of said blocks.
10. 3. A fuse having a casing provided with slots and perforations, contact members supported by said casing, a plurality of blocks in said casing, trunnions upon said blocks and adapted to be received in said slots, and 15 projections from the inner end of said blocks adapted to engage perforations in said casing to retain said blocks in position, a fuse link received upon said blocks as herein specified.
10. 4. An inclosed fuse having a casing contact members arranged at each end thereof, blocks within said casing and interior to the end thereof, each block being provided with an integral projection entering the wall of 25 said casing, trunnions upon said blocks for supporting said blocks, a fuse link engaged between each said block and the contact
- member adjacent thereto and screws extending parallel with the axis of said casing for clamping the ends of said fuse link into 30 electrical contact with said contact members.
5. A cartridge fuse having a cylinder, a cup-shaped member at one end thereof, a block wholly within said cylinder and mov- 35 ably secured therein, and a fuse link adapt- ed to be engaged between said block and said cup-shaped member.
6. A fuse having a casing provided with slots, and a perforation, a contact member 40 supported by said casing, a block in said casing, trunnions upon said block adapted to be received in said slots, and a projec- tion from said block adapted to engage said perforation to retain said block in position, 45 and a fuse link received upon said block as herein specified.

Signed at New York city, in the county and State of New York, this 2nd day of April, 1917.

HENRY MANNING COGAN.
